beater shaft 29 will be provided with a bevel gear 45 which meshes with a corresponding gear 46 on the table shaft 47 to revolve the table, (Fig. 7).

In Fig. 6 I have shown another means for imparting a beating action to the beaters and referring thereto an arm 48 is pivoted at 49 on the block 36 and is arranged to engage a lug 50 on the beater 39. An extension 51 on the arm 48 carries a roller 52 which rides against a cam 53. A spring 54 is connected to the beater and to the standard 38. When the block 36 is pushed upward by the link 35 the arm 48 engages the lug 50 and causes the beater 39 to swing upward to the broken line position. At the same time the roller 52 is traveling on the cam 53 and by the time the beater has reached the limit of its upward movement the cam has withdrawn the arm from engagement with the lug so that the spring may impart a beating action to the beater.

Instead of a rotative table, it may be desirable to provide a longitudinally reciprocating table, and referring to Figs. 8-10 55 is a table provided with grooved wheels 56 arranged to travel on tracks 57 mounted on the supporting frame 58. Chains 59 travel on idle sprockets 60 and driving sprockets 61 and these chains carry pins 62 which project upward into slots 63 in the table. The idle sprockets 60 are mounted on shafts 64 supported in bearings 65 on the frame 58 and the driving sprockets 61 are mounted 35 on driving shafts 66 supported in bearings 67 on the frame, and also carrying bevel gears 68 which mesh with bevel gears 69 on the shaft 70, which is driven by belt 71 from the beater shaft 29. In this construction the 40 beaters are mounted on standards opposite the ends of the beater shaft 29, as in Figs. 1 and 2, and they operate on the mattress while it is reciprocated with the table back and forth on the tracks 57 by the operation 45 of the chains. This table is reciprocated longitudinally. In the construction of Figs. 1 and 2 the table is rotatively reciprocated and in the construction of Fig. 7 the table is continuously rotative.

In Figs. 11 and 12 I have shown another means for imparting a beating action to the beaters, and referring thereto the beater 39 is pivotally mounted at 40 on the standard 38, as before described, and a block 72 is reciprocated by a link 73 which is connected to the wrist pin 34 just like the link 35. However, the link 73 is somewhat longer than the link 35 so that the block 72 may be carried to a greater elevation than is the case with the block 36. A roller 74 is mounted on the block to engage the beater 39 and lift the beater to its elevated position, as shown in broken lines in Fig. 11. A hook 75 is provided on the block to travel along the cam 76 face 77 of a latch 77, which is pivoted at 78

on the standard 38. This latch has a hooked end 79 which is arranged to be projected by the spring 80 beneath the beater 39 when the latter has been elevated, thereby to hold the beater temporarily in its elevated position. When the link 73 moves the block 72 downward the hook 75 travels on the cam 76, and as the block nears its lowest position the latch is swung on its pivot to disengage the hook end 79 from the beater whereupon the spring 81 pulls the beater down with a snappy blow upon the mattress.

In all the constructions the aim is to have the beaters operate with a beating movement upon the mattress, and this action may be made light or heavy, as required, by adjusting the springs. Should it be desired to impart to the beaters a simple reciprocating movement, the lugs 43 and springs 44 may be removed, or a single link may be substituted for the togle link 41, in which case the beaters would operate with a regular movement and at a fixed rate of speed.

My invention provides a machine of simple construction for beating mattresses to distribute the filling evenly throughout the tick and make the mattress uniform in density throughout. The apparatus is automatic in operation and the position of the mattress is constantly being changed with relation to the beaters so that the beaters will operate upon the mattress at different places in every successive operation of the machine.

I am aware that changes in the form, construction and arrangement of parts of my invention may be made without departing from the spirit or sacrificing the advantages thereof, and I reserve the right to use the machine for any other purposes for which it is or may be adapted besides beating mattresses, and also to make such changes therein as fairly fall within the scope of the following claims.

I claim:

1. The combination of a table for supporting a mattress or other article, a standard adjacent the table, a beater pivotally mounted on the standard, and means for imparting a reciprocating movement to the beater comprising a crank shaft, a block guided in said standard, a connection between the block and the beater for lifting the beater on the upward movement of the block, and a spring connected to the beater and to the standard for imparting an accelerated downward movement to the beater to beat the mattress.

2. The combination of a table for supporting a mattress or other article, means for imparting a rotative reciprocating movement to the table, a pair of standards located adjacent to the table on opposite sides thereof, a pair of beaters pivotally mounted on said standards, a beater shaft, blocks
